6 Claims. (Cl. 260—475)

This invention is directed to a method for the preparation of methyl esters of polycarboxylic aromatic acids. More particularly, this invention is directed to a process for the substantially simultaneous production and esterification of aromatic polycarboxylic acids.

The preparation of methyl esters of polycarboxylic aromatic acids presents many difficulties, not only with respect to the preparation of the polycarboxylic aromatic acids from alkyl aromatic hydrocarbons but also with respect to the esterification of such acids. Thus, when the acids are to be prepared by the oxidation of polyalkyl aromatic hydrocarbons with molecular oxygen, it is found that the oxidation reaction is carried to completion only with great difficulty and that serious problems are encountered with respect to by-product formation and product purification. For example, the air oxidation of a first alkyl group of a polyalkyl benzene results in the formation of a refractory alkylated benzoic acid which is highly resistant to further oxidation. As a consequence, the air oxidation of a second alkyl group is accomplished only with great difficulty. Moreover, the acids, once prepared, are only sparingly soluble in methanol and are therefore difficult to esterify.

It has now been surprisingly discovered that methyl esters of polycarboxylic aromatic acids may be directly prepared from polyalkyl aromatic hydrocarbons with ease by bringing oxygen into contact with a mixture of a liquid polyalkyl aromatic hydrocarbon under liquid phase oxidation conditions with a molar excess of a liquid methyl alcohol in the presence of a catalytic amount of a heavy metal salt. Thus, a product is obtainable wherein at least one (and preferably all) of the alkyl groups of the polyalkyl aromatic feed stock are converted to methyl ester groups.

More particularly, the present invention comprises a liquid phase process for the oxidation of polyalkyl aromatic hydrocarbons with molecular oxygen in the continual presence of an excess of liquefied methanol and the substantial absence of volatilized methanol, the process being catalyzed with a catalytically effective amount of a polyvalent metal oxidation catalyst. When this is done, oxidation of the methanol is surprisingly minimized and esterification of carboxyl groups is surprisingly enhanced. In addition, the presence of surprisingly large amounts of water in the liquid phase does not substantially adversely affect the process.

The starting material for the present invention is a substantially wholly aromatic hydrocarbon feed stock containing at least one aromatic hydrocarbon ring substituted with a plurality of C₁ to C₄ alkyl groups. Thus, the feed stock may consist of a single purified polyalkyl aromatic hydrocarbon or may comprise a mixture of a plurality of polyalkyl aromatic hydrocarbons or even a mixture of one or more polyalkyl aromatic hydrocarbons with an unsubstituted aromatic hydrocarbon or a monoalkyl aromatic hydrocarbon, or both. By way of example, the starting compounds, which may be used alone or in admixture include polymethyl benzenes (o-, m-, and p-xylene; pseudocumene; mesitylene; hemimellitene; durene; isodurene; prehnitene; pentamethyl benzene, and hexamethyl benzene), the corresponding polyethyl, poly-n-propyl, polyisopropyl, polybutyl, and polyisobutyl ben-

2

zenes, and the corresponding polybenzyls such as polyalkyl substituted di- and tri-benzyls. Representative examples of such additional feed stocks include o-, m-, or p-cymene; 1,2-, 1,3-, or 1,4-diethyl benzene; 1-methyl-3-butyl benzene; 1-methyl-4-tert.-butyl benzene; 1,2-, 1,3-, or 1,4-diisopropyl benzene; 1,2,4- or 1,3,5-triethyl benzene; 1,2,3,4- or 1,2,4,5-tetraethyl benzene, etc. As indicated, compounds as above described may be used alone and in admixture with each other or in admixture with other aromatic hydrocarbons such as benzene, monoalkyl benzenes (e.g., toluene, ethyl benzene, isopropyl benzene), or both.

The amount of methanol that is required is dependent upon a number of factors. In general, in excess of one mol of methanol is required per mol equivalent of alkyl group to be oxidized. More preferably, about 1.5 to about 3 mols of methanol should be used per mol equivalent of alkyl groups to be oxidized. Thus, if it is desired to convert a xylene to the corresponding methyl diester, there may be used, for example, a total of from about 3 to about 6 mols of methanol per mol of xylene (i.e., 1.5 to about 3 mols of methanol per mol equivalent of methyl group to be oxidized).

The manner in which the methanol is added to and maintained in the reaction mixture may vary, provided only that the methanol that is introduced is maintained substantially (preferentially) in the liquid phase after its introduction. It is not practical to maintain all of the methanol in liquid phase. For example, if dry air is used as the source of molecular oxygen, there will be a tendency for the methanol in liquid phase to saturate the air with methanol vapor. In addition, the gases that flow through the liquid reaction mixture will tend to entrain droplets of the liquid components including hydrocarbons, methanol, and water. However, in accordance with the present invention, the process is conducted so as to maximize the amount of methanol that is maintained in the liquid phase. Thus, by way of definition, the methanol is preferentially maintained in the liquid phase when methanol is lost from the liquid phase to the vapor phase only by saturation of the charged air and by entrainment. All of the required amount of methanol may be added with the fresh feed. Preferably, however, only a portion of the alcohol is added with the fresh feed and the remaining portion is added periodically or continually during the course of the reaction. Accordingly, in batch operations all of the methanol may be added at the beginning of the reaction or may be periodically or continually added during the course of the reaction. In continuous operations, a single stage may be employed with all of the methanol being mixed with the fresh feed. A plurality of stages may be employed with fresh methanol being added to each stage.

The catalysts to be utilized in accordance with the present invention are salts of polyvalent heavy metals such as the naphthenates, acetates, bromides, chlorides, etc. of cobalt, manganese, etc. Mixtures of two or more such heavy metal salts may be utilized if desired. At least a catalytically effective amount of catalyst should be employed. Thus, an amount of catalyst compound may be used which is sufficient to maintain about 0.05 to about 0.8 weight percent of catalyst in soluble catalytically effective form in the liquid reaction mixture. Larger amounts of catalyst (e.g., up to about 10 percent) may be employed, if desired, but this is not absolutely necessary. The amount of catalyst to be used, as set forth above, is calculated with respect to the weight of the heavy metal of the catalyst compound and the polyalkyl aromatic hydrocarbon feed stock.

Promoters for the oxidation reactions, the esterification reactions, or both, may be and preferably are employed in catalytically effective amounts. Thus, soluble

bromine salts such as cobalt bromide, ammonium bromide, manganese bromide, etc., acids such as hydrobromic acid, hydrochloric acid, or sulfuric acid may be employed in catalytically effective amounts. Normally, from about 0.5 to 2 volume percent of promoter is employed, based on the total charge. A preferred promoter is hydrogen bromide. This compound has several advantages. Thus, it is characterized by high promotional activity, both with respect to the oxidation reactions involving the polyalkyl aromatic feed stock and the esterification reactions involving the methanol and aromatic acids produced by oxidation of the alkyl aromatic feed stock but does not promote oxidative degradation of the methanol.

The reaction conditions to be employed are, in general, the reaction conditions that are normally employed in the liquid phase air oxidation of polyalkyl aromatic hydrocarbons in the substantial absence of liquid methanol. However, it has been discovered, in accordance with the present invention, that when such conditions are employed in the presence of liquid methanol, both oxidation and esterification reactions are promoted while oxidative decomposition of the liquid methanol to liquid non-aromatics is largely inhibited and oxidation of the methanol to gaseous products such as carbon dioxide and water is almost completely suppressed.

The reaction conditions to be employed should include a temperature within the range of about 140° to about 250° C. The pressure employed should be sufficient to maintain the methanol substantially exclusively in liquid phase. Accordingly, for temperatures within the range of about 140° to about 250° C., the pressure employed may be, correspondingly, within the range of about 200 to 1000 p.s.i.g.

When this is done, only a minimized amount of the methanol will be present in the reactor in vapor phase, for the reasons set forth above. This is desirable in that side reactions of the alcohol are thereby minimized. If this is not done, substantial degradation of the methanol will occur.

The oxidizing medium to be employed is oxygen, including pure oxygen, air, etc. Although the oxygen charge rate is not particularly critical, for convenience of reaction it is generally preferable to employ an oxygen charge rate such that, with the gas-liquid contacting available, an oxygen utilization of 50 percent or greater is accomplished. The oxygen charge rate should be correlated with the rate of reaction that is obtainable. With poor gas-liquid contacting, the reaction rate will be slow and comparatively low oxygen flow rates should be employed. With good agitation, good gas-liquid contacting is obtained whereby substantially higher reaction rates can be achieved and correspondingly higher oxygen flow rates can be utilized.

Preferably, the oxygen charge rate will be balanced with oxygen consumption so that the tail gas will be substantially completely free from unreacted oxygen. When the source of molecular oxygen is air, it is desirable that the tail gas contain not more than about 15 volume percent of oxygen. Oxygen flow rates which will cause entrainment of excessive amounts of methanol should be avoided.

Surprisingly large amounts of water may be tolerated in conducting the process of the present invention. However, when excessively large amounts of water are present, both esterification and oxidation rates are retarded. Of course, the water of reaction may be removed substantially contemporaneously with its evolution in order to maintain a substantially anhydrous condition within the reactor. However, this is not necessary to the practice of the present invention. Since the substantially complete removal of water from the reaction system without vaporization of the methanol is technically difficult, if not impossible, it is an advantageous feature of the present invention that substantial quantities of water (about 2 to 4

moles of water per mole of aromatic components) may be permitted to accumulate in the liquid phase without severely, adversely affecting the economics of the process. The amount of water that is permitted to accumulate in the reaction mixture should not be so excessive as to unduly dilute the methanol. Thus, it is preferable that the liquid methanol comprise at least 15 weight percent of the liquid phase, and still more preferably from about 20 to about 50 weight percent.

It is preferable to employ a continuous process with by-product purges as needed. As indicated, it is within the scope of the present invention to conduct the process in a single stage or in a plurality of stages. When a plurality of stages are employed, all of the fresh feed may be introduced into the first stage and the first stage may be operated in a manner to at least partially oxidize a substantial portion of the fresh feed (e.g., 60 to 95 mol percent) and to esterify a substantial portion (e.g., 60 to 90 mol percent) of the carboxyl groups formed by the oxidation reaction. That is to say, in the first stage oxygen addition to the fresh feed is the important consideration and no attempt is made to drive the oxidation and esterification reactions to completion. The oxidation and esterification reactions are thereafter completed in subsequent stages.

By-product water of reaction may be permitted to accumulate in the liquid phase of each stage but is preferably removed from the discharge material from the stage before the material is charged to a subsequent stage. Thus, the total product from each stage may be freed from water and alcohol oxidation byproducts by distillation and various other means familiar to those skilled in the art.

The invention will be further illustrated with respect to the accompanying drawings wherein:

FIG. 1 is a schematic flow sheet illustrating one manner in which a continuous single stage process may be conducted in accordance with the present invention; and

FIG. 2 is a schematic flow sheet illustrating one manner in which the present invention may be practiced employing a plurality of stages.

SINGLE STAGE PROCESS

Turning now to FIG. 1, there is shown a reaction zone 200 such as a corrosion resistant (e.g., glass-lined or titanium) reactor provided with suitable agitating means such as an impeller 202.

Fresh methanol for the process is introduced by way of a charge line 204 leading to an incorporator 206. Recycle methanol to be obtained in a manner to be described may be added to the charge line 204 by either a recycle line 208, a recycle line 210, or both.

A feed stock consisting essentially of aromatic hydrocarbons and containing at least a predominant amount of a polyalkyl aromatic hydrocarbon is charged from a suitable source (not shown) by way of a charge line 212 to the incorporator 206. A compound of a catalytically effective heavy metal such as cobalt naphthenate, together with a suitable promoter such as hydrogen bromide, may be added to the charge line 212 by way of the catalyst charge line 214 controlled by a valve 216. Recycle products obtained in a manner to be described may be added to the aromatics charge line 212 by way of a recycle line 218, a recycle line 220 controlled by a valve 222, or both.

The thus-prepared reaction mixture is discharged from the incorporator 206 by way of a line 224 leading to a preheater 226 wherein the charge is heated. The heated charge is introduced into the reaction zone 200 by way of a charge line 228. A suitable source of molecular oxygen such as air is introduced into the reactor 200 by way of oxygen charge line 230.

Within the reaction zone 200, the polyalkyl aromatic hydrocarbon feed stock is at least partially oxidized and a substantial portion of the carboxyl groups that are formed as a result of the oxidation reactions are esterified.

fied with the methanol. As a consequence, there is formed in the reaction zone 200 a liquid reaction mixture containing unreacted feed stock components, unreacted methanol, aromatic feed stock oxidation products, esterification products, and liquid methanol degradation by-products.

Off-gas will accumulate above the level of the liquid in the reaction zone and will contain nitrogen (when the source of oxygen is air), unreacted oxygen, if any, minor amounts of carbon dioxide, or carbon monoxide, or both, and such amounts of the feed components and reaction products as are present in the gas. The off-gas is withdrawn from the reaction zone 200 by way of a vent line 232 adjacent the top of the reaction zone leading to a cooler 234 wherein condensable components of the off-gas are liquefied. The resultant mixture of liquids and gases is discharged from the cooler 234 by way of a charge line 236 leading to a separating drum 238. The uncondensed gas is vented from the settling drum 238 by way of a vent line 240 and discharged from the system.

Condensed components of the off-gas will include unreacted methanol and methanol by-products, unreacted aromatic feed stock and conversion products derived from the aromatic feed stock. The condensed liquid is discharged from the settling drum 238 by way of a bottoms discharge line 242 and may, if desired, be returned from thence to the reaction zone 200 by way of a recycle line 244 controlled by a valve 246. More preferably, however, the condensed liquids are processed in order to remove at least the water and methanol by-products from the system. This may be accomplished, in accordance with one procedure, by routing the condensed liquids by way of a line 248 controlled by a valve 250 to a separation zone to be subsequently described.

Alternately, the condensed liquids are charged to a settling drum 252 by way of a charge line 254 controlled by a valve 256 which branches from the line 248.

Within the settling drum 252, the condensed liquids are separated into an aqueous phase and an oil phase containing principally components derived from the aromatic feed stock. The oil layer may be discharged from the drum 252 by the previously mentioned recycle line 218 leading to the aromatics charge line 212.

The aqueous phase may be discharged by way of a line 258 leading to a fractionation zone of any suitable construction wherein water and methanol by-products may be removed.

By way of example, the separation zone may comprise a first distillation column 260 and a second distillation column 262. The aqueous material is charged to the first distillation column by way of the line 258 and separated therein into a water fraction which is discharged from the bottom of the tower by way of a bottoms discharge line 263 for discard from the system. An overhead product is taken from the first distillation column 260 by way of a line 264 leading to the second distillation zone 262. Within the second distillation zone 262, the charge material therefor is separated into a substantially anhydrous methanol bottoms fraction which is discharged by way of the above-mentioned line 208 leading to the methanol charge line 204. Methanol by-products such as methylal and methyl formate are taken overheads by way of a line 266 for discard from the system.

Returning now to the reaction zone 200, a liquid product stream is continuously discharged by way of a product line 268 leading to a flash drum 272. As a result of a reduction in pressure, water, methanol, methanol by-products, and entrained oily material derived from the aromatic hydrocarbon feed stock are volatilized whereas the principal portion of the unreacted feed stock and conversion products thereof remains liquid. The oil layer is discharged from the flash drum 272 by a line 273 leading to a line 294 for further processing in a manner to be described.

The vapors from the flash drum 272 are taken over-

head by way of a line 274 leading to a cooler 276 wherein substantially all of the components of the vapor fraction are liquefied. The liquefied material is discharged from the cooler 276 by way of a line 278 leading to a settler 280. If desired, the valve 256 in the line 254 leading to the settling drum 272 may be closed and the valve 250 in the line 248 may be opened whereby condensed liquids obtained from the off-gas may be added to the charge line 278 to the settler 280 by way of the previously mentioned line 248.

Within the settling drum 280, an oil phase and an aqueous phase collect. Off-gas, if any, is discharged from the settler 280 by way of a vent line 282. The aqueous phase is withdrawn by way of a line 284 leading to a separation zone for the removal of water and methanol by-products. Suitably, the separation zone comprises a third distillation column 286 and a fourth distillation column 288. Within the third distillation column 286, the aqueous phase is separated into a bottoms water fraction which is discharged by way of a bottoms line 289 for discard from the system. The lighter material, consisting principally of methanol and methanol by-products, is taken overhead by way of a line 290 leading to the fourth distillation column 288. In the fourth distillation column 288, a substantially anhydrous methanol bottoms fraction is obtained which is discharged by way of a line 210 leading to the methanol charge line 204. Methanol by-products are taken overhead by way of a line 291 for discard from the system.

The oil fraction from the settler 280 is discharged by way of a line 292 containing the branch line 220 controlled by valve 222 which leads to the aromatics charge line 212 and a branch line 294 controlled by a valve 296 leading to a separation zone 298. All or a selected portion of the oil introduced into the line 294 may be charged to the separation zone 298. If desired, a selected fraction of the oil may be directly recycled to the reaction zone 200 from line 294 by way of the line 220 leading to the aromatics charge line 212.

Within the separation zone 298, a polymethyl ester of a polycarboxylic acid may be separated from the products of the reaction by any suitable technique such as distillation, fractional crystallization, or a combination process involving both distillation and fractional crystallization. The thus-recovered product is discharged from the system by a products discharge line 300 and the remaining material is recycled to the line 220 by way of a line 302.

OPERATION

By way of a specific example of a process conducted in the apparatus shown in FIG. 1, the charge material may be mesitylene and the desired product may be trimethyl trimesate. In this situation, a feed material which may consist essentially of mesitylene is introduced by way of the charge line 212 and is mixed in the incorporator 206 with an amount of methanol sufficient to provide, by way of example, about 6 mols of methanol per mol of mesitylene. An oxidation catalyst such as cobalt acetate and a promoter such as hydrogen bromide are mixed with the mesitylene by way of the catalyst charge line 214. The resultant feed stream that is formed in the incorporator 206 is passed through the preheater 226 and from thence to the reaction zone 200 wherein the methyl groups on the mesitylene are oxidized ultimately to carboxyl groups and wherein the carboxyl groups are esterified with the methanol. It will be understood that in a continuous process the oxidation catalyst and promoter will be added at a replacement rate and that fresh mesitylene will be added in an amount equivalent to the amount of trimethyl trimesate that is recovered in a manner to be described. Similarly, the fresh methanol is charged in an amount equivalent to the amount consumed through esterification and degradation.

For the purpose of the present discussion, it may be assumed that the valves 246 and 256 in the lines 244 and

254, respectively, are closed. In this situation, off-gas from the reaction zone 200 is cooled in cooler 234 to condense liquefiable material contained therein. Uncondensable off-gas is vented from the system by way of vent line 240 and the condensable material is charged by way of the line 248 to the line 278 leading to the settler 280.

The product stream is continually discharged from the zone 200 by way of the product discharge line 263 and flashed in the drum 272 to separate light components from the aromatic material present in the reaction product stream. The aromatic material will include a wide mixture of materials such as unreacted mesitylene, partial oxidation products thereof, partial esterification products, and fully oxidized fully esterified material which, in this 15 instance, will be trimethyl trimesate.

The gaseous material taken overhead by way of the line 274 from the zone 272 is condensed in the cooler 276 and charged from thence by way of the line 278 to the settling drum 280. Residual oil components, if any, are discharged from the settling drum 280 by way of the line 292 for further processing and the aqueous phase is discharged by way of the line 284 for separation in the distillation columns 286 and 288 into a water fraction, an anhydrous methanol fraction, and a by-product fraction. Water is discarded from the system by way of the bottoms discharge line 289 for the column 286 and by-products are discarded from the system by way of the overheads line 290 leading from the column 288. The anhydrous methanol is recycled by way of the line 210.

The aromatic material from the flash drum 272 is discharged by way of the bottoms discharge line 273 and has admixed therewith aromatic material discharged from the settling drum 280 by way of the line 292.

Preferably, a major portion of the resultant mixture is directly recycled to the aromatics charge line 212 by way of the recycle line 220 controlled by the valve 222. A minor portion of the mixture is charged by way of the line 294 controlled by a valve 296 to the separation zone 298. In the separation zone 298, purified trimethyl trimesate is recovered and discharged by way of a line 300. Partial conversion products of the mesitylene are returned to the recycle line 220 by way of the line 302.

PLURAL STAGE REACTION

A manner in which a continuous process may be conducted in accordance with the present invention in a plurality of stages is shown in FIG. 2.

Turning now to FIG. 2, there may be provided a head reactor 10 and at least one tail reactor 12. The reactors may suitably be provided with agitating means of any desired construction such as impellers 14 to 16, respectively.

A polyalkyl aromatic hydrocarbon feed stock such as paraxylene from a suitable source (not shown) is charged by way of a charge line 18 to a suitable mixing device such as a baffle plate incorporator 20 and is there mixed with catalyst charged by way of the line 22, methanol charged by way of the line 24 controlled by a valve 26, and preferably a recycle fraction 28 obtained in a manner to be described. As indicated, in excess of 1 mol of methanol per methyl group to be oxidized is charged. Catalyst is charged by way of line 22 in a replacing amount in order to maintain the desired rate of reaction.

The reaction medium is discharged from the incorporator 20 by way of a line 30 containing a preheater 32 leading to the reactor 10.

In this fashion, the mixture is charged to the reactor at a reaction temperature within the range of about 140° to about 250° C. The pressure is adjusted so as to maintain the methanol substantially exclusively in liquid phase. Air or any other suitable source of oxygen is charged to the reactor by way of an air injection line 34 at such a rate that with the available gas-liquid contacting, an

oxygen utilization of about 50 percent or greater is obtained.

Within the reactor 10, an oxidation reaction is initiated which, under the above-disclosed conditions, results in the preferential oxidation of the methyl groups on the aromatic hydrocarbon feed stock whereby such methyl groups may be ultimately converted to acid groups. Such acid groups, under the reaction conditions involved, are rapidly esterified with the methanol present. Only minimized side reactions of the methanol occur, whereby not more than about 0.5 to 1 mol of alcohol is converted to other than ester products per mol equivalent of ester formed. Only a minor amount of the methanol is degraded to carbon dioxide and water.

When air in the oxidizing medium, as shown, the off-gas containing entrained reaction components is discharged by way of a vent line 36 adjacent the top of the reactor 10 and passed through a cooler 38 to condense entrained or volatilized normally liquid components contained therein. The remaining gas is vented from the system by way of a vent line 40 controlled by a valve 42 and the condensed liquids are returned to the system by way of a reflux line 44 controlled by a valve 46. The condensed liquids may include methanol, methanol degradation products, water, hydrocarbon feed, and oxidation products thereof.

Alternately, the valve 46 in the reflux line 44 is closed whereby the condensed liquids are charged by a branch line 48 controlled by a valve 50 to a settler 52 where 30 the aqueous phase separates from the oil phase. In this situation, the oil phase may be returned to the reflux line 44 by way of a return line 54 controlled by a valve 56 and the aqueous phase may be discharged by way of a line 58 controlled by a valve 59. Preferably the aqueous 35 phase, rather than being discharged from the system, is charged by way of a branch line 60 controlled by a valve 61 to a fractionation zone to be described. In this situation, the amount of methanol withdrawn by way of the line 58 is continually replaced with an appropriate amount 40 of methanol charged by way of the line 24 whereby the desired molar excess of methanol is maintained in the reactor 10.

The average residence time of the feed stock within the reactor 10 should preferably be sufficient to provide 45 for the conversion of an average of at least one of the methyl groups of the xylene to an ester group. Thus, the residence time should preferably be such that about 60 to 90 percent of the xylene feed stock is at least partially converted.

50 A product side stream is withdrawn from the reactor 10 by way of a discharge line 62 leading to a first fractionation zone 64. The first stage product 62 is preferably mixed with the recycle fraction 60 described above and a recycle fraction 66 to be subsequently described prior to 55 introduction into the fractionation zone 64. The fractionation zone 64 is represented in the drawing as a single distillation column. It will be understood, of course, that one or a plurality of distillation columns may be employed in the zone 64. Thus, the charge to 60 the fractionation zone 64 will be comprised of a mixture of unreacted feed stock, at least partially reacted feed stock, methanol, methanol degradation products, water, catalyst components, etc. Within the fractionation zone 64, the mixture is split into a light fraction 68 containing 65 methanol, water, and, in the case of incomplete fractionation, entrained oily materials. The light fraction 68 is cooled in a cooling zone 70 and charged to a separator 72 wherein any entrained hydrocarbon materials are separated from an aqueous methanol solution by phase separation. The oily phase is discharged by way of a line 74 controlled by a valve 76 and the aqueous phase is discharged by way of a line 78.

75 The aqueous phase is charged to a second fractionation zone comprising, for example, a first distillation column 80 and a second distillation column 82. The aqueous

fraction 78 is initially charged to the column 80 wherein a light fraction composed principally of methanol oxidation by-products removed overhead by way of the line 83.

The bottoms fraction consisting essentially of methanol, water, and entrained catalyst components is discharged by way of a line 84 leading to the second distillation column 82. Within the second column 82, the aqueous medium is separated into a substantially anhydrous methanol fraction 85 which will also contain entrained catalyst components. The methanol fraction 86 may be discharged from the system but preferably is recycled by way of a recycle line 88 controlled by a valve 90. Thus, all or a portion of the methanol recovered by way of the line 86 may be recycled to the methanol charge line 24 leading to the incorporator 20.

Returning now to the first fractionation zone 64, a heavier fraction composed principally of unreacted xylene and at least partial conversion products thereof is discharged by way of a line 92 and, in admixture with entrained oil charged thereto by way of the line 74, is charged to a second incorporator 94 wherein the material is mixed with an amount of methanol at least sufficient to replace that withdrawn overhead from the zone 64 by way of the line 68. The methanol may be charged to the incorporator 94 by way of a charge line 96 controlled by a valve 98. All or a desired portion of the methanol may be recycle methanol introduced into the line 96 by way of a branch line 100 controlled by a valve 102 interconnecting the methanol charge line 96 with the alcohol recycle line 88.

The thus-reconstituted partially converted reaction mixture is discharged from incorporator 94 by way of a line 104 containing a preheater 106 leading to the second reactor 12. The charge mixture for the second reactor 12 may be heated to a temperature within the range of 140° to 250° C. which is the same as or different from the temperature employed in the reactor 10. Air or other suitable oxygen-containing gas is charged to the reactor 12 by way of a charge line 108 at a rate such that, with the available gas-liquid contacting, an oxygen utilization of about 50 percent or greater is obtained.

Within the reactor 12, additional conversion of the hydrocarbon charge material occurs including further oxidation of methyl groups and further esterification of carboxyl groups. Off-gas is discharged by way of a vent line 110 leading to a cooler 112 wherein condensable liquids including water, methanol, methanol by-products, and aromatic components are condensed. Uncondensable gases consisting principally of nitrogen are discharged from the cooler by way of a line 114 and the condensed material is discharged by way of a reflux line 116 controlled by a valve 118.

As before, the condensed liquids may alternately be charged by way of a branch line 120 controlled by a valve 122 leading to a separator 124 wherein an aqueous phase and an oil phase are formed. The aqueous phase may be discharged from the system by way of a discharge line 126 controlled by a valve 128. Preferably, the aqueous phase is recycled by way of a branch line 130 controlled by a valve 132 leading to the charge line 66 for the fractionation zone 64.

In this situation, the oil phase is returned to the reactor 12 by way of a return line 134 controlled by a valve 136 and an amount of methanol is added by way of the methanol charge line 96 sufficient to replace methanol withdrawn by way of the line 130.

A stream of oxidation products is withdrawn from the reactor 12 by way of a discharge line 138 leading to a third fractionation zone 140.

Within the zone 140, the product is separated into a lighter fraction composed of conversion products having a boiling point less than the boiling point of a desired esterified aromatic product. A bottoms fraction is discharged from the zone 140 by way of a line 142 leading

to a second fractionation zone 144 wherein a desired product is obtained overhead by way of a line 146 and wherein a heavier fraction is discharged by way of a bottoms line 148. All or a selected portion of the bottoms fraction 148 may be discharged from the system by way of a branch line 150 controlled by a valve 152. Alternately, the heavier fraction may be recycled to the initial incorporator 20 by way of the recycle line 28.

The product fraction discharged from the zone 144 by way of the line 146 may consist of fully esterified polycarboxylic aromatic acid (e.g., dimethyl terephthalate). Alternately, the fractionation conditions may be adjusted so that the product stream 146 also includes partially esterified aromatic polycarboxylic acid components. In this situation, the incompletely esterified material may be charged by way of a branch line 154 controlled by a valve 156 to an incorporator 158 wherein the material may be mixed with an excess of methanol charged by way of a line 160 controlled by a valve 162. A suitable esterification catalyst such as a mineral acid may be added by way of a charge line 164 controlled by a valve 166.

The mixture may be discharged from the incorporator 158 by way of a line 168 containing, if necessary, a preheater 169 and leading to an esterification zone 170 containing suitable agitating means such as an impeller 172. Within the esterification zone 170, the esterification of the aromatic carboxylic acid material is driven to completion under suitable esterification conditions. A product stream may be withdrawn from the esterification zone 170 by way of a line 174 leading to a separation zone 176 wherein the product stream may be separated into a methanol phase and an ester phase. The ester phase, consisting essentially of fully esterified aromatic carboxylic acid, is discharged by way of a discharge line 178 and the methanol phase is recycled (e.g., to the methanol charge line 160 by way of a recycle line 179). In order to prevent an undue build-up of water in the system, at least a portion of the methanol phase may be delivered by way of a branch line 180 controlled by a valve 182 to the charge line 84 for the fractionation zone 64.

OPERATION

By way of a specific example of the manner in which a dimethyl terephthalate may be obtained from paraxylene, the following sequence may be followed.

At least about 3 mols of methanol per mol of paraxylene in the mixing zone 20 and a suitable amount of oxidation catalyst such as cobalt naphthenate. Hydrogen bromide is also added.

The thus-prepared reaction mixture is charged to the reactor 10 wherein at least about 90 percent of the paraxylene is converted to oxidation products. That is to say, an average of about 1 of the methyl groups per molecule is at least partially oxidized and at least a substantial portion of the carboxyl groups that are formed are esterified.

A product stream is withdrawn from the reactor 10 by way of the line 62. The product stream will contain oxidation products of paraxylene, including dimethyl terephthalate, methyl paratoluate, monomethyl terephthalate, methyl benzoate, paratolualdehyde, paratoluic acid, paraxyl alcohol, unreacted paraxylene, and also methylal, methyl acetate, methyl formate, methanol and water.

The mixture is fractionated in the described manner to provide an essentially aqueous phase which is discharged overhead by way of the line 68 from the fractionation zone 64 and a heavy essentially oil phase discharged by way of the bottoms line 92. The oil phase 92 will consist essentially of unconverted paraxylene and the oxidation-esterification products thereof.

The heavy phase 92 is charged to the incorporator 94 wherein it is mixed with an amount of methanol sufficient to provide at least about 3 mols of methanol per mol of initial paraxylene charge stock. The resultant mixture

11

is charged to the second reactor 12 by way of the line 104 wherein the production of dimethyl terephthalate and monomethyl terephthalate is maximized. The product stream 138 withdrawn from the reactor 12 will contain essentially the same components as were charged thereto but in different amounts.

The product stream 138 is charged to a zone 140 wherein an overheads fraction 66 is obtained containing substantially all of the methanol and byproducts thereof. A heavy phase containing paraxylene oxidation products is withdrawn from the zone 140 by way of a line 142 leading to a fractionation zone 144 wherein an overheads product fraction 146 is obtained and wherein a bottoms recycle fraction 148 is obtained which may be recycled by way of the line 28.

The overheads fraction 146 may consist of dimethyl terephthalate, in which event this will be the final product. Alternately, the overheads fraction 146 may consist of a mixture of dimethyl terephthalate with monomethyl terephthalate. In this situation, the mixture may be charged by way of the branch line 154 to the incorporator 158 wherein an additional substantial excess of methanol may be added, together with an acidic esterification catalyst such as a mineral acid. The resultant mixture is charged to the esterification zone 170 wherein esterification is driven to completion. The esterification product is discharged by way of a line 174 leading to a separation zone 176.

A product fraction consisting essentially of dimethyl terephthalate is discharged by way of a line 178 and a methanol fraction is discharged by way of a discharge recycle line 179.

The invention will be further illustrated by way of the following specific examples which are given by way of illustration and not as limitations on the scope of this invention.

Example I

A mixture of methanol and orthoxylene was prepared, the mixture being proportioned so as to contain about 3 mols of methanol per mol of orthoxylene. To this mixture there was added about 2 percent cobalt acetate, about 2 percent manganese acetate and about 2 percent hydrogen bromide (based on the weight percent of the mixture). The resultant mixture was then subjected to a 2-stage oxidation-esterification reaction. Reaction conditions in the first stage included a temperature of about 360° F. (about 180° C.), a pressure of about 550 p.s.i.g., and a flow rate of about 1 volume of total feed per reactor volume per hour. Air was flowed through the reactor at a rate to provide maximum oxygen utilization, in this case at the rate of about 15 moles of air per mol of orthoxylene per hour. The composition of the total reactor product from the first stage is set forth in Table I.

TABLE I.—PRODUCT DISTRIBUTION, STAGE I

Product component:	Weight percent
Dimethyl phthalate	3.4
Monomethyl phthalate	10.9
Methyl benzoate	1.3
Methyl orthotoluolate	2.8
Orthotoluic acid	4.5
Orthotoluic acid	18.7
Phthalide	9.4
Orthoxylene	4.4
Orthoxyl alcohol	1.2
Methylal	2.8
Methyl acetate	1.4
Methyl formate	0.5
Methanol	20.3
Water	18.4

The total product from stage 1 was fractionated in order to separate methanol, water, methyl formate, methyl acetate, and methylal from the reaction mixture. The remaining material, consisting of orthoxylene and oxida-

12

tion products thereof, was charged to the second stage, together with an added amount of methanol sufficient to provide about 3 mols of methanol per mol of xylene-type compounds. Since the catalyst components initially charged to the first reaction zone were present in the oil phase, no additional catalyst was added.

The second stage reaction conditions included a temperature of about 390° F. (about 200° C.), a pressure of about 700 p.s.i.g., a flow rate of about 0.5 volume of total feed per reactor volume per hour, and an air charge rate of about 15 mols of air per mol of xylene-type compounds per hour. The total product from the second stage was recovered and analyzed and found to have the composition set forth in Table II.

TABLE II.—PRODUCT DISTRIBUTION, STAGE II

Product Component	Wt. Percent	Selectivity
Dimethyl Phthalate	18.9	25.4
Methyl Orthotoluolate	4.8	8.2
Monomethyl Phthalate	23.7	34.0
Methyl Benzoate	2.1	3.9
Phthalide	8.7	16.8
Orthotoluic acid	1.2	2.5
Orthoxylene	3.8	7.0
Orthoxyl Alcohol	0.2	0.5
Methylal	0.8	1.7
Methyl Acetate	2.5	-----
Methyl Formate	0.6	-----
Methanol	1.5	-----
Water	18.7	-----
	11.5	-----

It will be observed from Table II that there was a high yield and selectivity to dimethyl phthalate and monomethyl phthalate.

From the foregoing Tables I and II, it will be further observed that phthalide formed in the first stage is partially converted in the second stage. Consequently, loss of orthoxylene through the formation of by-product phthalide may be avoided by recycle of the phthalide inasmuch as the phthalide is converted under the process of the present invention to dimethyl phthalate.

It is to be noted that all of the agents necessary for the process were added in the beginning in this experiment. That is to say, both the heavy metal catalyst and the hydrogen bromide were added to the first stage. Replenishment was not required for the second stage reaction. Thus, when additional hydrogen bromide was added during the second stage reaction sequence, there was no observable effect. It is to be further observed that less than about 2 percent of the charge stock (orthoxylene and methanol) was converted to off-gas components such as carbon dioxide.

When paraxylene is substituted for orthoxylene and the example is otherwise repeated, equivalent results are obtained. In this instance, of course, phthalide is not present in the product.

Example II

In order to illustrate the need for maintaining the methanol in liquid phase as much as possible, a comparison was made with respect to the results set forth in Example I wherein methanol converted to by-products amounted to about 2 mols per mol of dicarboxylic acid yield and the results of the experiment described below.

The test run which was made for comparative purposes was a batch run with respect to the orthoxylene to be converted in that all of the xylene was charged at the beginning of the run. However, the run was semi-continuous with respect to methanol. The charge stock for the experiment was a mixture of methanol with orthoxylene proportioned so as to provide for about 4 mols of methanol per mol of orthoxylene. In addition, about 2 weight percent of cobalt acetate, about 2 weight percent of manganese acetate and about 2 weight percent of hydrogen bromide were added. The above weight percentages are calculated as weight percentages based upon the weight of the mixture. The reaction was conducted

at a temperature of about 380° F. and air was charged at the rate of about 10 mols of air per mol of orthoxylene charge per hour. In this instance, however, the reaction pressure was lowered to about 450 p.s.i.g. whereby a relatively large amount of condensate was obtained from the off-gas. This was attributable to the fact that the reaction was conducted in this instance very near the boiling point of methanol and water. The condensate which contained both water and methanol was not returned to the reactor, but an equivalent amount of dry methanol was continually supplied during the course of the reaction. In this manner, the water concentration in the reactor was minimized. However, a high throughput of methanol in the vapor phase was necessary in order to accomplish this result. After about 4 hours of operation, the condensate was collected and analyzed to determine the amount of methanol converted to by-products and the products of the reactor were analyzed to determine the xylene conversion. It was found that a yield of about 70 percent of dicarboxylic material had been obtained. However, more than about 9 mols of methanol were converted to by-products per mol of dicarboxylic product.

Thus, under comparable conditions of temperature, concentration, residence time, and yield of dicarboxylic material, but with large amounts of methanol in the vapor phase and a low concentration of water in the reactor, about 5 times as much methanol was converted to by-products as compared with Example I.

Example III

A mixture of methanol with mesitylene in the ratio of about 6 mols of methanol per mol of mesitylene was prepared. To the mixture was added about 2 weight percent each of $\text{Co(OAc)}_2 \cdot 4\text{H}_2\text{O}$ and $\text{Mn(OAc)}_2 \cdot 4\text{H}_2\text{O}$ plus about 2 percent of hydrogen bromide. The resultant mixture was reacted for about 6 hours under reaction conditions including a temperature of about 185° C., a pressure of about 500 p.s.i.g., and a gas flow rate of about 9 mols of air per mol of mesitylene charge per hour.

Since a complete analytical procedure was not available for analyzing the products from the above example, the following procedure was employed. Light materials such as methanol and water were evaporated from the product. Fresh methanol was added to the product (6 mols of methanol per mol of feed) in order to convert all of the acid components of the product to esters. This was done in order to simplify the analysis. The esterification reaction was conducted at a temperature of about 160° F. with anhydrous hydrogen chloride being continually added as catalyst. At the end of about 4 hours, the esterification mixture was cooled to room temperature and a substantial amount of crystalline material precipitated. This material was collected and dried and analyzed. It was found to consist of essentially pure trimethyl trimesate.

Example IV

To a mixture of p-diisopropyl benzene with methanol in the ratio of about 4 mols of methanol per mol of diisopropyl benzene there was added about 2 weight percent each of $\text{Co(OAc)}_2 \cdot 4\text{H}_2\text{O}$ and $\text{Mn(OAc)}_2 \cdot 4\text{H}_2\text{O}$. The resultant reaction mixture was reacted for about 5 hours under reaction conditions including a temperature of about 175° C., a pressure of about 500 p.s.i.g., and an air flow rate of about 9 mols of air per hour per mol of diisopropyl benzene. A substantially constant volume of liquid material was maintained in the reactor by replacing condensable materials carried with the off-gas as vapors with equivalent amounts of methanol. As a 70

consequence, oxidation of the p-diisopropyl benzene was initiated and esterification of carboxyl groups formed by the oxidation was initiated. After about 1 hour of reaction, aqueous hydrogen bromide (48 percent solution) was introduced in order to promote the oxidation and esterification reactions.

Since a complete analytical procedure was not available for analyzing the products from the above reaction, the following procedure was employed. Methanol and water were removed from the reaction mixture and the remaining oil solids were slurried in boiling methanol and filtered hot. On cooling, the crystals that precipitated from the filtrate were recovered and were dissolved in hot methanol. On cooling, a crystalline product was obtained which was found by analysis to consist essentially of pure dimethyl terephthalate.

What is claimed is:

1. In a method of preparing a product aromatic compound containing at least one methyl ester group by reacting in the liquid phase a polyalkyl aromatic hydrocarbon having from 1 to 4 carbon atoms in each alkyl substituent with methanol and molecular oxygen in a reaction zone in the presence of a catalytically effective amount of a polyvalent heavy metal containing oxidation catalyst, the improvement which comprises conducting the reaction at a temperature and pressure correlated to maintain said methanol preferentially in the liquid phase, whereby oxidative degradation of methanol is minimized.

2. A method in accordance with claim 1 wherein the polyalkyl aromatic hydrocarbon is a xylene.

3. In a method of preparing a product aromatic compound containing at least one methyl ester group by reacting in the liquid phase a polyalkyl aromatic hydrocarbon having from 1 to 4 carbon atoms in each alkyl substituent with methanol and molecular oxygen in the presence of a catalytically effective amount of a polyvalent heavy metal containing oxidation catalyst at a temperature within the range of about 140° C. to about 250° C. and at a pressure within the range of about 200 p.s.i.g. to about 1000 p.s.i.g., the improvement which comprises conducting the reaction at a temperature and pressure correlated to maintain said methanol preferentially in the liquid phase and in a concentration within the range of from about 15% to about 50%, whereby oxidative degradation of methanol is minimized.

4. A method in accordance with claim 3 wherein the polyalkyl aromatic hydrocarbon is a xylene.

5. In a method of preparing dimethyl terephthalate by reacting in the liquid phase p-xylene with methanol and molecular oxygen in the presence of a catalytically effective amount of a polyvalent heavy metal containing oxidation catalyst at a temperature within the range of about 140° C. to about 250° C. and at a pressure within the range of about 200 p.s.i.g. to about 1000 p.s.i.g., the improvement which comprises conducting the reaction at a temperature and pressure correlated to maintain said methanol preferentially in the liquid phase and in a concentration within the range of from about 15% to about 50%, whereby oxidative degradation of methanol is minimized.

6. A method in accordance with claim 5 wherein the catalyst is a soluble salt of cobalt.
